UNITED STATES PATENT OFFICE.

WILLIAM F. HARRISON, OF HARTFORD, CONNECTICUT, ASSIGNOR TO THE PRATT & CADY COMPANY, OF SAME PLACE.

THROTTLE-VALVE.

SPECIFICATION forming part of Letters Patent No. 608,197, dated August 2, 1898.

Application filed September 30, 1897. Serial No. 653,582. (No model.)

To all whom it may concern:

Be it known that I, WILLIAM F. HARRISON, a citizen of the United States, residing at Hartford, in the county of Hartford and State of Connecticut, have invented certain new and useful Improvements in Throttle-Valves, of which the following is a specification.

This invention relates to those throttle-valves which are arranged so that they may, 10 from the immediate vicinity or from distant points, be set in operation and caused to stop the flow of fluid in the supply-pipes with which they are connected.

The object of the invention is to provide a 15 simple, inexpensive, and durable valve of this nature having a stop-disk which when the spindle is turned to open the valve will first move slowly, and then after the pressure of the fluid is relieved will move rapidly and 20 open very quickly to a position where it will be held by a catch until released, and when the catch is tripped will be moved very rapidly in a reverse direction by automatically-operating closing means which act quickly 25 and shut the valve tightly.

The embodiment of the invention illustrated in the accompanying drawings has a valve-disk connected with a spindle that is so supported as to have imparted when rotated 30 for opening or closing the valve a longitudinal movement which results from the joint actions of several threaded parts that are brought into combined operation by their peculiar engagement, the spindle when 35 a valve is open being held from rotation by a catch that is adapted to be tripped by mechanism operated from near at hand or from distant points, as the emergency arises, and when released being rotated automatically by 40 mechanisms in which power for this purpose is stored by the act of rotating the spindle for opening the valve, as more particularly hereinafter described, and pointed out in the claims.

45 Figure 1 of the views shows a throttle-valve which embodies the invention, parts of this figure being cut in section to illustrate the construction. Fig. 2 shows a view of the hand-wheel end of this valve. Fig. 3 shows 50 a section taken on plane indicated by the broken line X X of Fig. 1. Fig. 4 shows a

detail section of a portion of a valve with a valve-disk of different construction.

The body 1 of the valve may be cast of iron, brass, or any other suitable metal to any approved shape, with flanged or screw-threaded ends, as desired, for attachment to the pipes of the system with which it is to be used. The valve-seat may be formed in the interior 55 of the body in any convenient manner, that shown being formed on the edge of a ring 2, that is threaded and screwed into a threaded recess in the walls of the body on one side of the disk-chamber, which is preferably provided with disk-guiding ribs 3.

A cover 4 is secured to the open end of the body in the customary manner, and through a suitably-packed perforation in this cover passes a spindle 5, that in the interior of the body bears a common valve-disk 6, which has 60 a proper face for making tight contact with the edge of the seat-ring.

Connected with the cover is a frame 7, that at the upper end bears a bushing 8 with an interior thread. The bushing shown is formed 75 by casting a suitable fine metal into the interior of the end of the base-metal frame. Supported by this bushing is an outer sleeve 9. This outer sleeve is provided with exterior threads that fit the threads in the bushing 8, and it is also provided with interior threads that fit exterior threads on an inner sleeve 10. The inner sleeve 10 also has interior threads that fit and mesh with threads on a portion of the spindle 5. This inner 80 sleeve 10 bears a collar 11, which has outwardly-projecting lugs 12, that move between ribs 13, formed on the frame, so that the sleeve 10 is held from rotation as it is reciprocated. The outer sleeve 9 supports a collar 14, provided with outwardly-extending 85 lugs 15 and 16, Fig. 1, and 17, Fig. 2.

Secured to the end of the spindle is a hand-wheel 18, and attached to this is a drum 19, around which is wound a cord 20, that supports a weight 21. When the hand-wheel is turned in one direction, the cord is wound up and the weight lifted, and then when the hand-wheel is free the weight will unwind the cord and rotate the hand-wheel and connected spindle in the opposite direction. If desired, of course, this power can be obtained

by means of a spring instead of the cord and weight shown.

Projecting inwardly from a part of the hand-wheel is a lug 22. In a chamber in the walls 5 of the frame is an outwardly-thrust spring-bolt 23, and engaging with this is a lever 24. The outer end of this spring-bolt projects into the path of the lug 17 except when it is drawn inwardly by a movement of the lever 10 24.

When the hand-wheel is turned to open the valve, the spindle rotates and simply travels outward with a movement that is determined by the pitch of its own thread that meshes 15 with the interior thread of the inner sleeve 10 until the lug 22 on the hand-wheel engages with the lug 15 on the collar 14. Then further rotation of the hand-wheel in the same direction with these lugs 22 and 15 in engagement rotates the outer sleeve 9, with which 20 the collar 14, bearing the lug 15, is connected. The rotation of the outer sleeve 9 causes that sleeve to travel outward with a movement that is determined by the pitch of its exterior 25 thread that engages with the interior thread in the stationary bushing 8 at the end of the frame. This longitudinal outward movement of the outer sleeve 9 carries out the inner sleeve 10, and the rotation of the outer 30 sleeve 9 also, through the meshing of its interior thread, causes the inner sleeve 10, that does not rotate, to be moved outward still faster. Of course as the inner sleeve 10 moves outward it carries the spindle bodily, 35 and this, added to the natural travel of the spindle incident to the pitch of its own thread, causes the spindle to be moved longitudinally very fast and the valve-disk to be drawn away from the seat, so as to open the valve 40 very rapidly.

When the valve is fully opened, the lug 17 is in position to be engaged by the spring-bolt 23, so that the collar 14 and outer sleeve cannot be rotated in a reverse direction until 45 the bolt is withdrawn from in front of this lug. The rotation of the hand-wheel winds up the weight-cord or spring, as the case may be, and stores up power for moving the parts in a reverse direction. When the hand is removed from the hand-wheel after winding up, the hand-wheel will rotate backward freely under the influence of the weight or spring until the lug 22 moves from contact with the lug 15 into contact with the lug 16 in position 50 by engagement with that lug when the bolt is withdrawn to rotate the collar 14 and sleeve 9, so as to close the valve. This initial movement causes the spindle to travel inward the distance it first moved outward under the pitch of its own thread in the sleeve 10, so that when the catch is released and the parts are rotated by the weight the disk will be carried back close against the seat and the valve tightly shut. The trip-lever can be operated 55 by hand or by a cord or wire leading to any distant locality, or by electrical or other common means that are employed for moving

tripping devices and which do not form a part of this invention.

This quick-operating mechanism may be 70 applied to a small or relief valve attached to a larger valve, as shown in Fig. 4. In this case the small valve-disk 25 is drawn from its seat on the large valve-disk 26 by the initial rotation and outward traveling of the spindle 75 under its own thread. This opens the valve, so that a portion of the pressure on the large disk is relieved, and then when the threaded sleeves commence to draw the spindle rapidly the parts so engage that the large disk is 80 drawn quickly from its seat. In closing this form the small disk will be shut against its seat by the rotation of the spindle when the valve is open and the opening power is removed from the hand-wheel. Then when the 85 catch is tripped the two disks will move together very rapidly and shut the valve tightly.

A valve embodying this invention can be opened very slowly when the disk is subjected to pressure, and then when the pressure is 90 relieved can be opened very rapidly. This valve can be arranged so as to be automatically closed from distant points when an emergency, like an accident to an operative or breaking of machinery, occurs and requires 95 that the engine be stopped at once, and when this valve thus arranged is tripped it will act so quickly that the fluid in the supply-pipe will be almost instantly cut off and the engine stopped. The mechanism of this valve 100 is simple and inexpensive to manufacture, not liable to get out of repair, positive in operation, and always ready for action.

I claim as my invention—

1. A throttle-valve having a body, a valve-disk within the body, a spindle connected with the disk, a sleeve with a thread fitting a thread on the spindle whereby longitudinal movement is imparted to the spindle when the spindle is rotated, and a connection between the spindle and the sleeve whereby the sleeve is also given a longitudinal movement when the spindle is rotated, substantially as specified.

2. A throttle-valve having a body, a valve-disk within the body, a spindle connected with the disk, an inner sleeve with a thread fitting a thread on the spindle whereby longitudinal movement is imparted to the spindle when the spindle is rotated, an outer sleeve connected with the inner sleeve, and a connection between the spindle and the outer sleeve whereby the inner sleeve is also given a longitudinal movement when the spindle is rotated, substantially as specified.

3. A throttle-valve having a body, a valve-disk within the body, a spindle connected with the disk, an inner sleeve with a thread fitting a thread on the spindle, an outer sleeve connected with the inner sleeve, and means for rotating and also for moving longitudinally the outer sleeve when the spindle is rotated, substantially as specified.

4. A throttle-valve having a body, a valve-

disk within the body, a spindle connected with the disk, an inner sleeve with a thread fitting a thread on the spindle, an outer sleeve with a thread fitting a thread on the inner sleeve, and means for rotating and moving longitudinally the outer sleeve when the spindle is rotated, substantially as specified.

5. A throttle-valve having a body, a valve-disk within the body, a spindle connected with the disk, an inner sleeve with a thread fitting a thread on the spindle, an outer sleeve with a thread fitting a thread on the inner sleeve, means for rotating and moving longitudinally the outer sleeve, and a trip device 10 for automatically restraining the rotation of the outer sleeve, substantially as specified.

6. A throttle-valve having a body, a valve-disk within the body, a spindle connected with the disk, an inner sleeve with a thread 15 fitting a thread on the spindle, an outer sleeve with a thread fitting a thread on the inner sleeve, a hand-wheel connected with the spindle, and lugs connected with the hand-wheel and with the outer sleeve arranged to engage 20 when the hand-wheel is rotated, substantially as specified.

7. A throttle-valve having a body, a valve-disk within the body, a spindle connected with the disk, an inner sleeve with a thread 25 fitting a thread on the spindle, an outer sleeve with a thread fitting a thread on the inner sleeve, a hand-wheel connected with the spindle, lugs connected with the hand-wheel and with the outer sleeve arranged to engage 30 when the hand-wheel is rotated, and a catch connected with the frame and arranged to temporarily engage a lug connected with the outer sleeve, substantially as specified.

8. A throttle-valve having a body, a valve-disk within the body, a spindle connected 35 with the disk, an inner sleeve with a thread

fitting a thread on the spindle, an outer sleeve with a thread fitting a thread on the inner sleeve, a hand-wheel connected with the spindle, lugs connected with the hand-wheel and with the outer sleeve arranged to engage 45 when the hand-wheel is rotated, a catch connected with the frame and arranged to temporarily engage a lug connected with the outer sleeve, and a lever for tripping the catch, substantially as specified.

9. A throttle-valve having a body, a valve-disk within the body, a spindle connected with the disk, an inner sleeve with a thread fitting a thread on the spindle, an outer sleeve 50 with a thread fitting a thread on the inner sleeve, a hand-wheel connected with the spindle, lugs projecting from the hand-wheel and from a part connected with the outer sleeve and arranged to engage when the hand-wheel 55 is rotated, a drum connected with the hand-wheel, means for rotating the drum, and a catch for temporarily holding the drum against rotation, substantially as specified.

10. A throttle-valve having a body, a main 60 valve-disk within the body, a supplemental valve-disk mounted upon the main valve-disk and adapted to have a small motion independently thereof, a spindle connected with the supplemental disk, a sleeve with a thread 65 fitting a thread on the spindle whereby longitudinal movement is imparted to the spindle when the spindle is rotated, and a connection between the spindle and the sleeve whereby the sleeve is also given a longitudinal movement when the spindle is rotated, substantially as specified.
